UNITED STATES PATENT OFFICE.

MEYER L. ROBBINS, OF NEW YORK, N. Y.

WATCH-BRACELET.

1,177,273.

Specification of Letters Patent.

Patented Mar. 28, 1916.

Original application filed October 29, 1915, Serial No. 58,576. Divided and this application filed February 5, 1916. Serial No. 76,311.

To all whom it may concern:

Be it known that I, MEYER L. ROBBINS, a citizen of the United States, and a resident of the city, county, and State of New York, have invented a certain new and useful Improvement in Watch-Bracelets, of which the following is a specification.

This invention relates to watch bracelets and especially those of the type known as "convertible" and the object of this invention is to provide a bracelet of this type wherein the watch can be readily detached and used for other purposes such as a brooch watch or chatelaine. When the ordinary bracelet watch is detached and used for other purposes the link secured to the watch to which the bracelet is attached is readily discernible and it can be seen that a bracelet watch is being used. By the use of my improved end link and means for connecting the same to the watch case, this advantage is avoided and the watch can readily be detached from the bracelet and worn in any other manner without it being known that a bracelet watch is being used. These and other improvements are carried out by my invention, a more particular description of which will appear below.

Referring to the accompanying drawings, annexed hereto and forming part hereof, Figure 1 is a plan view of my improved attaching link as secured to the watch, a portion of the watch case being shown; Fig. 2 is a perspective view of the securing member of the attaching link; Fig. 3 is a plan view of the attaching link in open position; Fig. 4 is a side view of the same; and Fig. 5 is a plan view, partly in section, of the clamp and means for holding the same in engagement with the watch case.

Throughout the various views of the drawings, similar reference characters designate similar parts.

This application is a division of my co-pending application, Ser. No. 58,576, filed October 29th, 1915.

My improved attaching link in which the invention resides, consists of an outer link or member which is formed of two trough-shaped members 1 connected at their ends by the cross members 2. The inner, or securing member 3 of the adjoining link engages one of the cross members 2, establishing a connection between the links. The securing member of the attaching link is

slidably mounted between the sides 1 of the outer member, and said securing member has a pair of resilient tongues 5 and 6. The lower tongue 6 is split longitudinally, as at 7, dividing it into two parts, each of which 60 parts has an offset arm 8, having studs 9 extending toward one another forming a pair of jaws for engaging the watch case between them, as will now be described.

The watch case 12 is provided with a hinge 11 in the usual manner and in the ends of said hinge 11 are recesses 10 into which the studs 9 extend. A collar 13 embraces the tongue 6 and is slidably mounted thereon. When moved toward the jaws it 70 tends to draw the same toward one another and hold the same into engagement with the recesses 10 in the watch case, and when said collar is moved backward on the tongue 6 it allows the jaws to spread whereby they 75 may be readily freed from engagement with the watch case and the link detached. Depressions 14 are placed in the tongue 6 adjacent the offset arms 8, into which the collar 13 fits so that the jaws are held into engagement with the watch case and an inadvertent disengagement therefrom is prevented. When it is desired to disengage the watch 80 from the bracelet the jaws are moved slightly toward one another so that the 85 collar can be moved out of the depressions and backward on the tongue 6 so that the jaws can spread and the studs 9 pass out of the recesses 10 in the watch case.

The upper tongue 5 of the securing member has a recess 15 in its upper side which engages with a cross member 16 on the outer link forming a locking connection between the securing member and the outer link and holding the locking member within the 95 outer link as shown in Fig. 1. A serrated portion 17 is formed on the tongue 5 adjacent its end so that the tongue 5 can be pressed down, whereby the recess 15 will move out of engagement with the cross 100 member 16 so that the securing member can be moved out of the outer link, as shown in Figs. 3 and 4 so that the collar 13 can be slid back on the tongue 6 allowing a spreading of the jaws when it is desired to remove 105 the watch from engagement with the bracelet. A recess 18 is formed in the outer link, into which the collar 13 fits.

It will be noted that it will be impossible for the jaws to spread until the securing 110

member has moved out of the outer link, as shown in Figs. 3 and 4, as it will be impossible for the collar 13 to move backward as the same is prevented from so doing by the recess 18 in the outer link against which it bears.

From the foregoing, it is obvious that my invention is not restricted to the embodiment herein shown, but is broad enough to cover all structures coming within the scope of the annexed claims.

Having described my invention, what I claim is:

1. A fastening means for bracelets and the like comprising an outer link, an inner securing member slidable therein, a portion of said securing member engageable with the outer link and forming a locking connection between said outer link and securing member, a clamp formed on said securing member for engaging a projection on a watch case and means movable on the securing member for drawing the sides of the clamp toward one another and holding the same in engagement with the watch case.
2. A fastening means for bracelets and the like comprising an outer link, an inner securing member slidable within the outer link, means on the securing member engaging means on the outer link and forming a locking engagement between the said outer link and securing member, a clamp having a pair of laterally distensible jaws for engaging a watch case formed on the securing member, and means on said securing member for drawing said jaws toward one another whereby the jaws are held in their contracted position in engagement with the watch case.
3. A fastening means for bracelets and the like comprising an outer link, a securing member slidable therein having a pair of tongues, means on one of said tongues for engaging means on the outer link to form a locking connection between the securing member and outer link, a clamp on the other tongue for engaging openings in a watch case, and means on said clamp for drawing the sides of the same toward one another whereby the said clamp is held in its con-

tracted position and into engagement with the watch case.

4. A fastening means for bracelets and the like comprising an outer link, a securing member having a pair of resilient tongues slidable within the outer link, a depression in one of said tongues for engaging a portion of the outer link whereby a locking connection is formed between the outer link and the securing member, a clamp formed on the end of the other tongue for engaging a pair of openings in a watch case and means movable on the clamp portion of the securing member for drawing together the sides of the clamp whereby the said clamp is held in engagement with a watch case.

5. A fastening means for bracelets and the like comprising an outer link, a securing member slidable therein having a pair of resilient tongues, one of said tongues being divided into a pair of resilient arms, said arms engaging openings in a watch case, a collar movable on said tongue for drawing the arms toward one another and holding the arms in engagement with the watch case, and means on the other tongue for engaging means on the outer link and forming a locking connection between the said outer link and securing member.

6. A fastening means for bracelets and the like comprising a watch case having a pair of openings therein, a detachable link having an outer member, a securing member slidable therein comprising a pair of resilient tongues, a recess on one of said tongues engaged by a cross piece on the outer member, the other tongue being divided to form a pair of arms, offset portions on said arms, studs adapted to engage the openings in the watch case on the ends of said offset portions and a sliding collar on the divided tongue for drawing the arms on said tongue together whereby the studs are retained in engagement with the openings in the watch case.

Signed at the city, county and State of New York, this 31st day of January, 1916.

MEYER L. ROBBINS.
